UNITED STATES PATENT OFFICE

154,745

DESIGN FOR A SOFA

Anthony J. Buckner, Jackson Heights, N. Y., assignor to Grosfeld House, Inc., New York, N. Y.

Application December 19, 1947, Serial No. 143,237

Term of patent 3½ years

(Cl. D15—11)

To all whom it may concern:

Be it known that I, Anthony J. Buckner, a citizen of the United States of America, residing in Jackson Heights, county of Queens, and State of New York, have invented a new, original, and ornamental Design for a Sofa, of which the following is a specification, reference being had to the accompanying drawing, forming part thereof, wherein,

The figure is a front perspective view of a sofa showing my new design.

The opposite end of the sofa is the same as that shown on the drawing, and the rear is substantially plain.

I claim:

The ornamental design for a sofa, substantially as shown and described.

ANTHONY J. BUCKNER.
